S. A. CRONE,
BRAKE BEAM,
APPLICATION FILED NOV. 3, 1916.

1,272,778.

Patented July 16, 1918.

Seth A. Crone INVENTOR
BY Charles C. Gill ATTORNEY

UNITED STATES PATENT OFFICE.

SETH A. CRONE, OF EAST ORANGE, NEW JERSEY.

BRAKE-BEAM.

1,272,778.

Specification of Letters Patent. Patented July 16, 1918.

Application filed November 3, 1916. Serial No. 129,282.

To all whom it may concern:

Be it known that I, SETH A. CRONE, a citizen of the United States, and a resident of East Orange, in the county of Essex and 5 State of New Jersey, have invented certain new and useful Improvements in Brake-Beams, of which the following is a specification.

The invention pertains more particularly 10 to trussed beams and especially to a novel strut having integrally therewith means for connecting the same with the compressed member of the beam. It is of the highest importance that the strut be securely connected 15 with the compression member in a manner which will be convenient and secure and not weaken said member. There has been difficulty in properly securing one piece forged metal struts to the compression member 20 of brake beams, and usually the strut at one end has extended around the compression member and been secured thereto by riveting, as shown in Letters Patent granted to me June 8, 1915 No. 1,142,498. 25 In other instances the strut has been secured against the compression member by bolts and clamps and in other instances by bolts and keys. My present invention has 30 for its object to secure the strut to a compression member by means integral with the strut and which engage the compression member with binding effect, the use of rivets, clamps, bolts and the like being obviated. My invention is applicable to 35 compression members of the various shapes commonly used, such as channels, angles and the like.

I present my invention herein as embodied in a brake beam of the character disclosed in my aforesaid Letters Patent dated 40 June 8, 1915, without however limiting my invention to the details of the said beam.

The invention will be fully understood 45 from the detailed description hereinafter presented, reference being had to the accompanying drawings, in which:

Figure 1 is a top view, partly broken away, of a brake beam constructed in accordance with and embodying my invention;

Fig. 2 is a vertical section through the same taken along the edge of the strut and therefore showing the strut in horizontal side elevation;

55 Fig. 3 is a side elevation of a portion of a brake beam embodying my invention, the

compression member in this instance being of angle shape as distinguished from the channel shape represented in Figs. 1 and 2;

Fig. 4 is a side elevation of a portion of 60 the strut applied to a channel compression member, which is shown in section, and Fig. 4 illustrates a modification of the construction shown in Figs. 1 and 2 in that the securing lips are shown as cut from the middle 65 portions of the metal constituting the strut instead of from the edge portions thereof; and

Fig. 5 is a corresponding view illustrating 70 the use of keys for insuring the binding action of the strut against the compression member.

In the drawings, referring to Figs. 1 and 2, 10 designates the compression member, 11 the truss-rod or tension member, and 12 the 75 strut, this strut being formed from a single piece of forged metal folded at its center and extending transversely around and engaging the compression member 10 and carrying at the outer or free ends of its sides a 80 metal socket 13 adapted to such ends and to receive the middle portion of the truss rod 11. The compression member 10 may vary 85 in cross-section, but I prefer to use a channel beam for the member 10, as illustrated in Figs. 1 and 2.

My invention may, however, be utilized with great advantage where the compression member is of angle shape, as is illustrated in Fig. 3, wherein 14 denotes the compression 90 member and 15 the strut.

The strut 12 is formed from a single bar of forged metal folded at its middle portion to form a box-loop 16 adapted to transversely encompass the compression member 95 10, whence the body portions of the folded bar are correspondingly deflected to form the parallel angular sides 17 adapted to receive between them in the usual manner the customary brake lever, not shown. The 100 sides 17 are at their outer ends connected, in the present instance, by a socket member 13 having at its outer end a groove to transversely receive the middle portion of the truss rod 11, and said sides reasonably adjacent to the compression member have between them a filler 18 through which and said sides extends a securing rivet 19. The 105 sides 17 are, at a suitable point, transversely apertured, as at 20, to receive the brake lever 110 pin, not shown.

In accordance with my invention I cut

from the metal of the sides 17, lips 21 and bend these lips inwardly against the adjacent edges of the compression member with binding effect, and preferably I cut the lips 21 from diagonally opposite edges of the sides 17 where said sides are deflected to give the brake lever its proper angle. The deflection of the sides 17 results in said sides adjacent to the beam 10 having an angular relation to said beam and in diagonally opposite edges of said sides being brought inwardly of the horizontal planes of the upper and lower surfaces of said beam, and it is at these two diagonally opposite points at which I preferably cut the tongues or lips 21. I prefer to cut the lips 21 from the edges of the sides of the strut, not only because of the convenience of doing so, but because when said lips are cut from the diagonally opposite edges of the side of the strut where said edges approach inwardly toward the horizontal center of the compression member, said lips may be used with the maximum effect in binding the strut and compression member together. Figs. 1 and 2 illustrate the manner of forming and the bending inwardly of the lips 21, and it will be seen that the lips exert a binding force against the edges of the flanges of the compression member and serve to bind the strut and compression member together, all riveting or other securing of the strut and compression member together by means not integral with the strut being obviated. In accordance with my invention I secure the strut to the compression member by means which are integral with the strut and dispense with rivets and other applied attachments.

The brake beam partly illustrated in Fig. 3 corresponds exactly with the brake beam shown in Figs. 1 and 2, with the exception that it presents an angle-beam compression member 14 and a box loop of angle shape at the outer end of the strut, as at 22, instead of the box loop 16, shown in Figs. 1 and 2. Fig. 3 being a modification I number the securing lips 23. The lips 23 are, however, identical with the lips 21, shown in Figs. 1 and 2 and employed for a corresponding purpose. The invention is highly useful in connection with an angle compression member, since it affords very simple and adequate means for securing the strut to the compression member without the use of applied clamping devices and the like.

Fig. 4 illustrates a modification of the invention in that the securing lips, numbered 24, are cut from the middle portions of the sides 25 of the strut 26 and bent inwardly against the edges of the flanges of the compression member 27 instead of, as in Figs. 1 and 2, being cut from the edges of the sides of the strut. The lips 24 shown in Fig. 4 are employed for exactly the same

purpose as the lips 21, shown in Figs. 1 and 2.

In Fig. 5 I illustrate the same construction presented in Fig. 4, with the addition of keys or wedges 28 which may be used, should occasion ever require, for tightening the binding action of the strut and compression member against each other. The purpose is that the lips 24 shall directly engage the edges of the compression member with sufficient force to effectually bind the strut in position, but in any event in which there should be any irregularity in construction or in the dimensions of the compression member whereby clearance might be created between the strut and said member, said clearance or play may be taken up by driving wedges or keys 28 along the edges of the compression member and between said edges and the inturned lips 24. The wedges or keys 28 will only be used when necessary to insure the rigid binding of the strut and compression member together.

What I claim as my invention and desire to secure by Letters Patent, is:

1. A brake-beam comprising a compression member having corresponding flanges, a tension member and a strut intermediate said members for the brake-lever, said strut being a forged metal folded bar encompassing said compression member and at the edges of said flanges being deflected angularly to form parallel sides for the brake-lever, and said bar adjacent to said compression member having a lip cut therefrom to initially project in a direction toward the tension member and being bent inwardly from said bar to present its inner flat face toward said compression member, for securing the strut and compression member together.

2. A brake-beam comprising a compression member having corresponding flanges, a tension member and a strut intermediate said members for the brake-lever, said strut being a forged metal folded bar encompassing said compression member and at the edges of said flanges being deflected angularly to form parallel sides for the brake-lever, and said bar at said angular portions having lips cut therefrom to initially project in a direction toward the tension member and being bent inwardly toward each other and presenting their inner flat faces toward the flanges of said compression member, for securing the strut and compression member together.

3. A brake beam comprising a compression member, a tension member and a strut intermediate said members for the brake lever, said strut being a forged metal folded bar encompassing said compression member, whence the members of the bar are deflected to form angularly disposed parallel sides, and having lips cut from the edges thereof

and bent inwardly for securing the strut and compression member.

4. A brake beam comprising a compression member, a tension member and a strut intermediate said members for the brake lever, said strut being a forged metal folded bar encompassing said compression member, whence the members of the bar are deflected to form angularly disposed parallel sides, and having lips cut from diagonally opposite edges thereof and bent inwardly for securing the strut and compression member, said lips being cut from those diagonally opposite edges where the side members of the strut are curved inwardly toward the compression member in the formation of the angular sides of the strut.

5. A brake beam comprising a compression member, a tension member and a strut intermediate said members for the brake lever, said strut being a forged metal folded bar encompassing said compression member, whence the members of the bar are deflected to form angularly disposed parallel sides, and having a lip cut from the edge thereof and bent inwardly for securing the strut and compression member. 20 25

Signed at New York city, in the county of New York and State of New York, this 1st day of November A. D. 1916.

SETH A. CRONE.
